(57) **CLAIM**

The ornamental design for a shoe, as shown and described.

DESCRIPTION

FIG. 1 is a perspective view of a shoe.

FIG. 2 is a side view of the shoe of FIG. 1.

FIG. 3 is a side view of the shoe of FIG. 1, from the opposite side as FIG. 2.

FIG. 4 is a front view of the shoe of FIG. 1.

FIG. 5 is a rear view of the shoe of FIG. 1.

FIG. 6 is a top view of the shoe of FIG. 1; and,

FIG. 7 is a bottom view of the shoe of FIG. 1.

The broken lines in the figures depict portions of the shoe that form no part of the claimed design.

1 Claim, 4 Drawing Sheets
